FIG. 1.

FIG. 2

A vertical strip of paper with handwritten numbers. The numbers are arranged as follows: 27 at the top, 30 below it, 15 in the middle, 49 at the bottom, and 28 on the right side. The numbers 30 and 15 are positioned close together in the center. The number 49 is at the very bottom. The number 28 is on the right edge of the strip.

UNITED STATES PATENT OFFICE.

HENRY KLECKLER, OF BUFFALO, NEW YORK, ASSIGNOR TO CURTISS AEROPLANE AND MOTOR CORPORATION, A CORPORATION OF NEW YORK.

WING CONSTRUCTION.

1,291,678.

Specification of Letters Patent. Patented Jan. 14, 1919.

Application filed March 31, 1916. Serial No. 88,094.

To all whom it may concern:

Be it known that I, HENRY KLECKLER, a citizen of the United States, residing at Buffalo, in the county of Erie and State of New York, have invented certain new and useful Improvements in Wing Construction, of which the following is a specification.

My present invention relates to aircraft equipment and more particularly to an improved supporting plane or wing of a construction designed to secure a maximum of rigidity and strength with a minimum of weight and resistance—characteristics essential to increased speed and lifting efficiency in a flying machine.

In describing my invention in detail, reference will be had to the accompanying drawings wherein like characters of reference designate like or corresponding parts throughout the several views, in which:

Figure 1 is a plan view of my improved wing structure stripped of its fabric covering;

Fig. 2 is an end view illustrating the general streamline form of the wing;

Fig. 3 is an enlarged detail transverse sectional view illustrating the wing nose construction;

Fig. 4 is a plan view illustrating in detail the manner in which one of the compression struts and wing beams are joined;

Fig. 5 is a view somewhat similar to Fig. 3 illustrating in elevation one of the web strips;

Fig. 6 is a view somewhat similar to Fig. 4 illustrating the connection between one of the web strips and the wing beams;

Fig. 7 is an enlarged section on the line 7—7 of Fig. 1;

Fig. 8 is a similar view on the line 8—8 of Fig. 1;

Fig. 9 is a similar view on the line 9—9 of Fig. 1;

Fig. 10 is a similar view on the line 10—10 of Fig. 1;

Fig. 11 is an elevation illustrating a modified form of compression strut;

Fig. 12 is an enlarged cross section on the line 12—12 of Fig. 1, and

Fig. 13 is a detail sectional view illustrating the wing-hinge construction.

The wing in its preferred embodiment comprises parallel wing beams 15 and 16

mounted to extend laterally of the body of the craft (not shown) in a direction transverse to the line of flight. The rear wing beam 16 is extended slightly beyond the end of the forward wing beam 15 at its outer end to obtain a somewhat greater spread at the trailing edge with resulting increased lateral stability. Each beam is tapered at its outer or free end as indicated at 16' that the thickness of the wing at said outer end may be materially reduced. Wing hinges 17 and 18 are utilized to effectually secure the wing structure to the fuselage, nacelle or other body structure (not shown). These wing-hinges are of a construction best illustrated in Fig. 13 and may be said to consist of hinge-plates 17' and a connecting portion 18', the former penetrating the inner end strut of the wing and engaging with the opposite longitudinal edges of the wing beam to provide for securement thereto as indicated at 15'. The connecting portion of each hinge bears against the inner face of the end strut and accordingly braces and limits movements of the hinge with respect to the wing.

While the wing herein illustrated is slightly cambered, and as illustrated in Fig. 2, set at an angle of incidence, it is to be understood that such a construction and arrangement is only preferred.

Compression struts, preferably five in number, transversely brace the wing beams, the several struts being disposed in parallelism and at varying distances apart, the distance between adjacent struts increasing from the inner to the outer end of the wing. From said inner end outwardly, the struts are designated respectively 19, 20, 21, 22 and 23, the inner strut having a greater cross-sectional dimension than the next adjacent strut and so on, the outer strut having the smallest cross-sectional dimension since the strain at the outer end of the wing is less than the strain at the inner end thereof. The inner strut 19, hereinafter referred to as the end strut, like the struts 20 and 21, extends laterally beyond the remote longitudinal edges of the wing beams 15 and 16 to secure at the inner end of the wing the desired streamline form. The outer struts 22 and 23 terminate abruptly at one end and flush with the rear wing beam 16 to afford at the outer

end of the wing an operating space or jog for the wing flap or aileron (not shown). The aileron or wing flap will continue the streamline form of the wing aft at the outer 5 end thereof and accordingly preclude the formation of vortices at the outer end of the wing.

The compression struts, except the end strut 19, are constructed alike, each strut 10 comprising a solid web portion 24, the longitudinal top and bottom edges of which engage in longitudinal grooves 25 and 26 formed respectively in cap-strips 27 and 28 glued or otherwise secured in place. The 15 mentioned strips together with the web portion constitute a compression strut of the desired I-form in cross section. The end strut 19 is hollow throughout and built up of a plurality of strips arranged in the manner 20 illustrated to advantage in Fig. 10. The side strips of the end strut, designated respectively 29 and 30 engage in grooves 31 and 32 formed respectively in the end strips 33 and 34 constituting with the said side strips 25 the hollow end strut. Such a construction 30 is conducive to rigidity, strength and lightness. By providing cap strips for each compression strut, a relatively flat securing surface is in evidence whereby the fabric covering (not shown) for the wing may be glued or otherwise secured in a manner precluding warping and sagging intermediate the several wing structure parts.

Web strips 35 extend parallel with the 35 compression struts and to a certain extent transversely brace the wing. Each web strip is laminated as illustrated in Fig. 9 and like the compression struts comprises a web portion 36 and cap strips 37 and 38. The top 40 and bottom longitudinal edges of the web portion 36 of each web strip is mounted to extend beyond the top and bottom edges respectively of the wing beams to engage in grooves therefor formed in the cap strips, 45 the groove in the cap strip 37 being designated 39 and the groove in the cap strip 38 designated 40. Such an arrangement will preclude lateral separation of the laminations constituting the web strips 36 and 50 offer to the fabric, as before pointed out, a relatively flat securing surface. The relatively deep web portion of each web strip is such that the cap strips lie flush upon the wing. Each web strip is materially lightened by the formation of lightening holes 41 therein.

Certain of the web strips like the inner compression struts extend beyond the remote longitudinal edges of the wing beams while 60 others terminate flush with the rear wing beam. The outermost extended web strip or that portion of the web strip defining the inner end of the jog is diagonally braced as indicated at 42 to the wing beam 16 and 65 transversely braced as indicated at 43 to the

extended web strip next adjacent thereto. The transverse bracing strips 43 extend in diverging relation from the outermost web strip and intersect the diagonal braces 42. Diagonal braces 44, 45 and 46 effectually 70 brace the end strut 19 to the respective beams 15 and 16, the braces 44 and 45 engaging with the rear wing beam and the brace 46 with the forward wing beam as illustrated in Fig. 1. Transversely extending diverging bracing strips 47 intersect the diagonal brace 44 and engage with the end strut 19 and with the web strip next adjacent thereto in much the same manner as the transverse brace 43. Both the transverse brace 43 and the transverse brace 47 brace the extended tail portion of the wing at a point equidistant from the wing beam and the trailing edge of the wing. A trailing edge strip 48 (preferably metallic) is mounted to interconnect the several struts and web strips which extend aft of the rear wing beam 16. By referring to Fig. 12 it will be observed that the web strips and struts complementally engage with the trailing edge strip 48 and that the cap strips overhang said strip 48 to which they are secured by a metallic strip 47' having an overall length sufficient to extend from the jog to the inner end of the wing. Said strip 47' is of a shape in 95 cross-section to overlap and securely fasten the terminals of the cap-strips to the tail strip of the wing.

A hollowed-out nose strip 49 (curved in cross-section) interconnects the several compression struts and web strips at the leading edge of the wing. If desired, bracing strips 50 may extend from the forward wing beam 15 to the nose strip 49 intermediate adjacent web strips. The several bracing strips, 100 compression struts and the web strips effectually support and brace a veneering strip 51 mounted to extend longitudinally of the wing and to engage respectively the nose strip 49 and the wing beam 15, the veneering 110 strip 51 in cross section being curved to secure a uniform and unbroken engaging surface for the fabric covering at the top leading edge of the wing. Upon a careful observation of Fig. 3 it will be noted that the 115 lower longitudinal edge of the nose strip is beveled as indicated at 49' to provide an abutment and securing surface for the cap strips extending forwardly beyond the forward wing beam 16. The opposite longitudinal edge of the nose strip is beveled as indicated at 48' to afford a relatively flat securing surface for the top or upper cap strips of the web strips and struts.

An angular outer end strip or compression strut 52 is located at the extreme outer end of the wing. Diagonal braces 53 and 54 extend from each the beam 15 and the beam 16 to the mentioned strut 52. Stringers 55 longitudinally brace the wing and 130

transversely brace the web-strips, the stringers engaging with each of the several compression struts and the web-strips at a point preferably equidistant from the wing beams 5 of the wing.

Compression strains incident to flight, are borne by drift wires 56 arranged in pairs within the wing structure to interconnect adjacent struts and to extend diagonally 10 from the forward end of one strut to the rear end of the strut next adjacent thereto. Turnbuckles 57 may be utilized to effectually tighten the wires 56. To brace the wing against strains imposed thereon in alighting, wires 58 are provided. The wires 58 like the drift wires 56 interconnect adjacent struts interiorly of the wing frame. The wires 58, however, intersect the wires 56 and accordingly oppositely brace the wing. 15 Both sets of bracing wires pass through the openings 41 in the web strips without contact with the strips at any point.

Upon reference to Figs. 3 and 4, it will be observed that the beams 15 and 16 are 20 I-formed in cross section to secure lightness without a proportionate decrease in strength. At the points where the compression struts engage with the wing beams, the mentioned beams or rather the web portion of each is 25 enlarged as indicated at 59 since the greatest strains incident to flight are imposed on the beams at the points where the struts engage therewith. Blocking 60 is interposed between each compression strut and each 30 wing beam to provide for the securement of a fitting 61 thereto. The blocking 60 also affords a foundation for the overhanging portion or portions of the wing post socket 60', since the mentioned socket as indicated 35 in Fig. 3 is of a size to extend beyond the opposite longitudinal edges of the wing beam to which it is secured. Each fitting 61 extends laterally beyond the edges of the strut against which it is fitted to thus 40 provide a means whereby the bracing wires 56 and 58 may be secured to the beams at the points where the struts intersect or engage. Bolts 62, one of which is an eye-bolt, penetrate the fitting or casting, the blocks 45 and the enlarged portion of the wing beam to secure the former in place without weakening the beam by reason of openings or bolt-holes formed therein. One of the drift wires of each pair is secured to the eye-bolt while the other of said wires is 50 secured to an ear 61' formed in the fitting 61. A second ear 58' is likewise formed on each fitting to provide for securement of the wires 58. To further obviate the necessity of weakening the wing beams at any 55 point, the bolt-holes 63 for the securing means for the wing post fittings (not shown) are formed in the blocks 60 at opposite sides of the wing beam and not in the 60 wing beam itself as heretofore. Blocks 64, 65

similar to the blocks 60, having bolt-holes 65 formed therein at opposite sides of the wing beam are adapted for securement to the beam at such points throughout its length as are designated to support various 70 fittings constituting the equipage of a flying machine. Fillers 65' are provided to build up the blocking 60 and the blocking 64 at opposite sides of the cap strips flush with the top surface of the veneering 51. 75

Bearing blocks 66' afford abutments for the several strut braces and receive directly the strains which would otherwise be imposed on the struts. Each bearing block thus acts as a strain distributing medium 80 in that the forces or strains exerted on the struts are directed longitudinally thereof or with the grain rather than transversely thereof and across the grain.

In referring to the modification illustrated in Fig. 11, the I-formed compression struts have been eliminated and tubular compression struts 66 substituted instead. The struts 66 are preferably metallic and mounted to engage in sockets 67 secured to 90 the respective wing beams by bolts 68 passing transversely therethrough. In other respects, the wing structure of the modified wing is the same as that hereinbefore described. 95

While I have described my invention in detail in its preferred embodiment it will be obvious to those skilled in the art after understanding the invention, that various changes and modifications may be made 100 therein without departing from the spirit or scope thereof and I aim in the appended claims to cover all such modifications and changes.

What is claimed is:

1. In a wing structure, wing beams, laminated web strips interconnecting the respective beams, and cap strips grooved to receive the respective longitudinal edges of the several web strips to secure the laminations against separation. 110

2. In a wing structure, wing beams, a nose strip, veneering interconnecting the forward wing beam and the nose strip to effectually preclude sagging of the wing covering intermediate said beam and said strip, and web strips interconnecting said beam and said nose strip to transversely brace the veneering from beneath. 115

3. In a wing structure, wing beams, a transversely extending compression strut, a bearing block interposed between one end of said strut and said beam to receive the compression strains, and a securing means for the mentioned block. 120

4. In a wing structure, wing beams, wing post sockets of a size such that the sockets extend beyond the opposite longitudinal edges of the respective beams, blocking interposed between the respective extended 130

terminals of the several sockets to afford a foundation therefor, and means for fastening the blocking to the beams.

5. In a wing structure, wing beams, compression struts transversely bracing the respective beams, wing fitting blocks mounted upon the beams at various points throughout the length thereof, a securing means for the mentioned blocks mounted to transversely penetrate both the blocks and the beams to which they are connected, a fitting interposed between the terminals of certain of said struts and the blocks secured to the wing beams, and bracing means for the wing secured to said fitting.

6. In a wing structure, wing beams, wing post sockets of a size such that the opposite longitudinal edges thereof extend beyond the corresponding edges of the beams, blocking interposed between the respective extended terminals of the several sockets to afford a foundation therefor and means penetrating the blocking without penetrating the beams for fastening the sockets to the beams.

7. In a wing structure, wing beams of I-form in cross section throughout the greater portion of their length, compression struts, and enlargements formed on the respective beams at the points where the respective compression struts engage therewith.

8. In a wing structure, wing beams, and web-strips of a relatively greater depth than the thickness of the respective beams to extend respectively above and below the beams at the terminals of the several strips.

9. In a wing structure, a wing beam, a longitudinally channeled nose strip, means entering the channel of said strip to prevent its displacement relatively to the beam, and means abutting and extending back from the edges of the nose strip, said last mentioned means affording a foundation for the wing covering of the wing characterized by an absence of breaks in its continuity.

10. In a wing structure, wing beams, wing

post sockets of a size to extend beyond the opposite longitudinal edges of the respective beams, blocking interposed between the respective extended terminals of the several sockets to afford a foundation therefor, and a means passing transversely through the blocking and through the wing beam to secure the former against displacement with respect to said beam.

11. In a wing structure, wing beams, compression struts connecting the respective beams, diagonally disposed strut-braces, and a bearing block interposed between each diagonal brace and its associated strut to distribute the strain imposed thereon longitudinally of the strut.

12. In a wing structure, a hollow box-like compression strut built up of a plurality of connected parts and wing beams let through one side of said strut for contact with the opposite side.

13. In a wing structure, a forward wing beam, a rear wing beam, a nose strip mounted forwardly of the front wing beam to extend parallel therewith throughout the greater portion of its length, the outer end of the nose strip being rearwardly extended to intersect the forward wing beam and contact the rear wing beam to serve conjointly as an outer edge strip, a trailing edge strip mounted aft of the rear wing beam to extend parallel therewith, the length of said trailing edge strip being considerably less than the length of the rear wing beam, and web strips interconnecting respectively the nose strip and the forward wing beam, the two wing beams, and the rear wing beam, and the trailing edge strip, the web strip at the outer end of the wing terminating squarely in alinement with the rear wing beam to provide a jog at the rear outer edge of the wing defined respectively by the rear wing beam and one of said web strips.

In testimony whereof I affix my signature

HENRY KLECKLER
